HERBICIDAL ANILINOMETHYLENE-
MALONONITRILES

Robert K. Howe, Bridgeton, and Joseph W. Baker, Kirkwood, Mo., assignors to Monsanto Company, St. Louis, Mo.

No Drawing. Filed Jan. 14, 1970, Ser. No. 2,961
The portion of the term of the patent subsequent to
Dec. 29, 1987, has been disclaimed

6 Claims

ABSTRACT OF THE DISCLOSURE

Herbicidal anilinomethylenemalononitrile compounds of the formula

wherein R_1 is selected from the group consisting of hydrogen, alkyl having a maximum of 8 carbon atoms and the group

in which R is an alkyl; A_1 , A_2 , A_3 , A_4 , and A_5 are independently selected from the group consisting of hydrogen, alkyl, halogen, haloalkyl, nitro, cyano, hydroxy, alkoxy, phenoxy, phenyl and substituted phenyl.

Herbicidal anilinomethylenemalononitriles

This invention relates to anilinomethylenemalononitrile herbicidal compositions and the related method of controlling the growth of plants.

This application is related to our application Ser. No. 681,578 filed Nov. 8, 1967, now U.S. Pat. No. 3,551,573.

The herbicidal anilinomethylenemalononitriles of this invention are represented by the formula

wherein R_1 is selected from the group consisting of hydrogen, alkyl having a maximum of 8 carbon atoms and the group

in which R is an alkyl of a maximum of 4 carbon atoms; A_1 , A_2 , A_3 , A_4 , and A_5 are independently selected from the group consisting of hydrogen, alkyl having a maximum of 8 carbon atoms, halogen (i.e. chlorine, bromine, fluorine, iodine), haloalkyl of a maximum of 8 carbon atoms, nitro, cyano, hydroxy, alkoxy of a maximum of 5 carbon atoms, phenoxy, carboalkoxy of a maximum of 8 carbon atoms,

2

wherein R_5 and R_6 are alkyl groups of a maximum of 5 carbon atoms, phenyl and substituted phenyl in which the substituents are the other groups defined by A_1 , A_2 , A_3 , A_4 and A_5 .

The preferred anilinomethylenemalononitrile compounds of this invention are represented by the formula

wherein R_1 is selected from the group consisting of hydrogen, alkyl of a maximum of 8 carbon atoms and the group

where R is an alkyl of a maximum of 4 carbon atoms; R_2 , R_3 and R_4 are each independently selected from the group consisting of hydrogen, alkyl of a maximum of 8 carbon atoms, hydroxy, alkoxy of a maximum of 5 carbon atoms, phenoxy, halogen, haloalkyl of a maximum of 8 carbon atoms, nitro, carboalkoxy of a maximum of 5 carbon atoms,

wherein R_5 and R_6 are alkyl groups of a maximum of 5 carbon atoms one of which is a secondary or tertiary carbon; and provided that when R_2 , R_3 and R_4 are alkyl branched on the alpha carbon and the haloalkyl is trichloromethyl, then they are on other than adjacent carbons.

Still more preferred compounds of the foregoing formula are where:

R_1 is alkyl of a maximum of 4 carbons or the group

and at least one of R_2 , R_3 and R_4 are methyl, halogen or halomethyl. The most preferred compounds of this group of compounds are those containing substituents in the meta or 3 position and especially in both meta positions or the 3 and 5 positions.

R_1 is hydrogen and R_2 , R_3 , and R_4 are selected from the group consisting of hydrogen, halogen, methyl, halomethyl, nitro and methoxy with the provision that at least two of R_2 , R_3 and R_4 are other than hydrogen. The most preferred compounds of this group of compounds are those containing substituents in the meta or 3 position and especially in both meta positions or the 3 and 5 positions.

The term "herbicide" as used herein and in the appended claims means materials which (1) effectively control the growth of all plants in a given locus or (2) selectively control the growth of one or more plant species in the presence of other plants.

The term "control" as used herein and in the appended claims is inclusive of the actions of (1) killing, (2) inhibiting growth, reproduction or proliferation, and (3) removing, destroying or otherwise diminishing the occurrence and activity of plants and is applicable to any of the stated actions, or any combination thereof.

The herbicides herein defined are suitable for controlling the growth of plants in pre-emergent and post-emer-

gent plant applications. That is, they are effective in controlling the growth of dormant seeds, germinant seeds, germinative seeds, emerging seedlings and established woody and herbaceous vegetation by exposing the seeds, emerging seedlings, or the roots or above-ground portions to the action of an effective amount of one or more of said anilinomethylenemalononitriles. However, the best results are obtained with the compounds of this invention in a post-emergence situation by spraying the compounds on the plants.

For the sake of brevity and simplicity, the term "active ingredient" is used hereinafter in the specification to describe the anilinomethylenemalononitrile compositions of this invention.

In foliar treatment for the modification of vegetative growth, the active ingredients are applied in amounts from about 0.1 to about 25 or more pounds per acre. In applications to soil for the modification of the growth of germinant seeds, germinative seeds, emerging seedlings and established vegetation, the active ingredients are applied in amounts from about 1 to about 50 or more pounds per acre. In such soil applications, it is desirable that the active ingredients be distributed to a depth of at least 0.2 inch. In selective pre-emergence herbicide applications the active ingredients are usually applied in amounts from about 1 to 50 pounds per acre but preferably from about 1 to 10 pounds per acre. It is believed that one skilled in the art can readily determine from the teachings of this specification, including the examples herein, the general procedure for any application.

The preparation of the various anilinomethylenemalononitriles of this invention is by known methods and in most cases consists in the reaction of the appropriate amine with ethoxymethylenemalononitrile as follows:

wherein R_1 , A_1 , A_2 , A_3 , A_4 and A_5 are as previously defined.

Reactions of substituted anilines with alkoxyethylene malononitriles are usually run at a temperature in the approximate range of about 10-150° C. The compounds are preferably dissolved in a suitable solvent including lower alkyl ethers and alcohols, such as diethyl ether, methanol, propanol and the like, and aromatic hydrocarbons such as benzene, toluene and the like. The reaction mixture is normally heated to the reflux temperature of the mixture and maintained at this temperature until the reaction is completed. The product is separated from the reaction mixture by conventional methods such as filtration, distillation, concentration and the like.

10 Having now described many ramifications and embodiments of the present invention, it is believed that an understanding thereof will be facilitated and made more full by the following examples. In these examples, as well as in the specification and appended claims, parts and percentages are by weight unless otherwise indicated.

EXAMPLE 1

To a suitable vessel equipped with an agitator, reflux condenser and thermometer was charged 22.9 parts (0.10 mole) of 3,5-di(trifluoromethyl)aniline and 12.2 parts (0.10 mole) of ethoxymethylenemalononitrile in 75 ml. ethanol and the mixture refluxed for 62 hours. The solution was then cooled, precipitating the product. The product was collected and washed with ethanol. Recrystallization from ethanol gave the product having a melting point of 234-236° C.

Analysis.—Calculated for $\text{C}_{12}\text{H}_5\text{F}_6\text{N}_3$ (percent): C, 47.22; H, 1.65. Found (percent): C, 47.44; H, 1.62.

40 Illustrative examples of other anilinomethylenemalononitrile compounds which were prepared (and in many cases their physical properties) are given in Table I.

^a Decomposition.## EXAMPLE 85

The pre-emergent herbicidal activity of the active ingredients of this invention is demonstrated as follows: A good grade of top soil is placed in aluminum pans and compacted to a depth of $\frac{3}{8}$ " to $\frac{1}{2}$ " from the top of each pan. A predetermined number of seeds of the test plant species are placed on top of the soil in the pans. The seeds are covered with a $\frac{3}{8}$ " layer of soil and the pan leveled. The active ingredient is applied by spraying the surface of the top layer of soil with a herbicidal formulation containing a sufficient amount of active ingredient to obtain the desired rate of active ingredient per acre. For soil incorporation, the chemical is sprayed on and mixed into the soil used to cover the seeds.

The seed-containing pans are placed on a wet sand bench and maintained under ordinary conditions of sunlight and watering. The plants are observed at the end of

approximately 14 days and the results recorded. The herbicidal activity index is based on the average percent control of each seed lot. The herbicidal activity index is converted to a relative numerical scale for the sake of brevity and simplicity in the table.

The pre-emergent herbicidal activity index used is defined as follows:

Average percent control	Numerical scale
0 to 25	0
26 to 50	1
51 to 75	2
76 to 100	3

In Table II following, the anilinomethylenemalononitrile compound, the dosage rate, method of application, the spectrum of plant seeds treated, and the results of the tests carried out according to the above procedure are indicated.

¹ Plant in week at application.

NOTE.—0.05% concentration equals approximately 1 pound per acre dosage rate here.

9
EXAMPLE 86

In a post-emergent herbicidal test, the active ingredients in each case is applied in spray form to 2 or 3 week old specimens of the plants (species indicated hereinafter). The herbicidal sprays are either wettable powder formulations or organic solvent-water solutions containing a surface active agent and varying amounts of the active ingredient. The solutions are applied to the plants in different pans at rates equal to the desired rate of active ingredient on a per acre basis. The treated plants are placed in a greenhouse and the effects are observed and recorded after approximately 14 days.

The post-emergent herbicidal activity index used in this example is defined as follows:

Numerical scale:	Herbicidal activity
0 -----	No phytotoxicity.
1 -----	Slight phytotoxicity.
2 -----	Moderate phytotoxicity.
3 -----	Severe phytotoxicity.
4 -----	Plants dead.

In Table III the anilinomethylenemalononitrile compound, dosage rate, the spectrum of plants treated and the results obtained by the above procedure are indicated.

In practicing the herbicidal methods of this invention, the active ingredients can be used alone or in combination with a material referred to in the art as an adjuvant in liquid or solid form. Herbicidal formulations are prepared by admixing the active ingredient with an adjuvant which includes diluents, extenders, carriers and conditioning agents, the latter of which are surface active agents (or as some prefer, surfactants) to provide compositions in the form of finely-divided particulate solids, granules, pellets, solutions, dispersions or emulsions. Thus the active ingredient can be used with an adjuvant such as a finely-divided particulate solid, a liquid or organic origin, water, a wetting agent, a dispersing agent, an emulsifying agent or any suitable combination of these. The herbicidal formulations usually contain from about 0.01 percent to about 99 percent by weight of active ingredient.

Typical finely-divided solids which can be used with the active ingredients include the talcs, natural and synthetic clays (e.g., kaolinites), fuller's earth, salt, powdered wood, ground corn cobs, cottonseed hulls, wheat flour, and the like. Typical diluents include petroleum fractions such as kerosene, hexane, benzene, acetone, ethylene dichloride, Stoddard solvent, alcohols such as propanol and the like.

Specific surface-active agents which can be used in the herbicidal formulations of this invention are set out, for example, in Searle U.S. Patent 2,426,417, Todd U.S. Patent 2,655,447, Jones U.S. Patent 2,412,510 and Lenher U.S. Patent 2,139,276. A detailed list of such agents is also set forth by J. W. McCutcheon in "Soap and Chemical Specialities," November 1947, page 8011 et seq., entitled "Synthetic Detergents"; "Detergents and Emulsifiers—Up to Date" (1960), by J. W. McCutcheon, Inc., and Bulletin E-607 of the Bureau of Entomology and Plant Quarantine of the USDA. In general, less than 50 parts by weight of the surface active agent is present per 100 parts by weight of herbicidal formulation.

Preferred wetting agents are alkyl benzene and alkyl naphthalene sulfonates, sulfated fatty alcohols, amines or acid amides, petroleum sulfonates, polyoxoethylene derivatives of alkylphenols (particularly isooctylphenol and nonylphenyl). Preferred dispersants are methyl cellulose, sodium naphthalene sulfonate, and sodium N-methyl-N-(long chain acid) taurates.

Wettable powder formulations usually contain from about 5 to about 95 parts by weight of active ingredient, from about 0.25 to 25 parts by weight of wetting agent, from about 0.25 to 25 parts by weight of dispersant and from 4.5 to about 94.5 parts by weight of inert solid extender, all parts being by weight of the total formula-

10

tion. Where required from about 0.1 to 2.0 parts by weight of the solid inert extender can be replaced by a corrosion inhibitor or anti-foaming agent or both.

Dusts are dense finely-divided particulate formulations which are intended for application to the soil in dry form. Dusts contain primarily an active ingredient and a dense, free-flowing finely-divided particulate extender. However, their performance is sometimes aided by the inclusion of a wetting agent such as those listed hereinbefore. The dusts usually contain from about 0.5 to 95 parts active ingredient, 0 to 50 parts wetting agent and 5 to 99.5 parts dense solid extender, all parts being by weight and based on the total weight of the dust.

The wettable powders described above may also be used in the preparation of dusts, however, it is more advantageous to dilute them by blending with the dense dust diluent. In this manner, dispersing agents, corrosion inhibitors, and anti-foam agents may also be found as components of a dust.

Emulsifiable oil formulations are usually solutions of active ingredient in water-immiscible or partially water-immiscible solvents together with a surface active agent. Suitable solvents for the active ingredient of this invention include hydrocarbons and water-immiscible ethers, esters or ketones. Suitable surfactants are found hereinabove. The emulsifiable oil formulations generally contain from about 5 to 95 parts active ingredient, about 1 to 50 parts surface active agent and about 4 to 94 parts solvent, all parts being by weight based on the total weight of the emulsifiable oil.

Granules are physically stable particulate formulations comprising active ingredient adhering to or distributed through a basic matrix of an inert, finely-divided particulate extender. In order to aid leaching of the active ingredient from the particulate, a surface active agent such as those listed hereinbefore can be employed.

The mineral particles which are used in the herbicidal formulations usually have a size range of 10 to 100 mesh, but preferably such that a large majority of the particles have from 14 to 60 mesh with the optimum size being from 20 to 40 mesh. Clay, having substantially all particles between 14 and 80 mesh and at least about 80 percent between 20 and 40 mesh, is particularly preferred to use in the herbicidal formulations. The term "mesh" as used herein means U.S. Sieve Series.

The granular herbicidal formulations generally contain from about 5 parts to about 30 parts by weight of active ingredient per 100 parts by weight of clay and 0 to about 5 parts by weight of surface active agent per 100 parts by weight of particulate clay. The preferred granular formulations contain from about 10 parts to about 25 parts by weight of active ingredient per 100 parts by weight of clay.

The herbicidal formulations can also contain other additaments; for example, fertilizers, other herbicides, plant growth regulants, pesticides and the like used as adjuvant or in combination with any of the above-described adjuvants.

While particular embodiments of the invention have been described, it will be understood, of course, that the invention is not limited thereto, since many modifications may be made; and it is therefore contemplated to cover by the appended claims any such modifications as fall within the true spirit and scope of the invention.

What is claimed is:

1. Herbicidal method which comprises applying to plants a herbicidally effective amount of an anilinomethylenemalononitrile compound of the formula

11

wherein R_1 is selected from the group consisting of hydrogen, alkyl having a maximum of 8 carbon atoms, and the group

wherein R is an alkyl of a maximum of 4 carbon atoms; A_1 , A_2 , A_3 , A_4 , and A_5 are independently selected from the group consisting of hydrogen, alkyl of a maximum of 8 carbon atoms, halogen, haloalkyl of a maximum of 8 carbon atoms, nitro, cyano, hydroxy, alkoxy of a maximum of 5 carbon atoms, phenoxy, carboalkoxy of a maximum of 8 carbon atoms,

wherein R_5 and R_6 are alkyl groups of a maximum of 5 carbon atoms, phenyl and substituted phenyl in which the substituents are the other groups defined in A_1 , A_2 , A_3 , A_4 and A_5 .

2. Herbicidal method according to claim 1 wherein R_1 is alkyl of a maximum of 8 carbon atoms.

3. Herbicidal method according to claim 2 wherein

12

at least one of A_1 , A_2 , A_3 , A_4 and A_5 substituents is methyl, halogen, or halomethyl and the remainder are hydrogen.

4. Herbicidal method according to claim 3 wherein at least one substituent is in a meta position.

5. Herbicidal method according to claim 2 wherein at least two of A_1 , A_2 , A_3 , A_4 and A_5 substituents are methyl, halogen or halomethyl, two of which are in meta positions and the remainder is hydrogen.

10 6. Herbicidal method according to claim 1 wherein said compound is applied to said plants subsequent to their emergence from the soil.
